UNITED STATES PATENT OFFICE.

JOHN A. COLE, OF CHICAGO, ILLINOIS, ASSIGNOR TO J. LIVINGSTON & CO., INC., OF NEW YORK, N. Y., A CORPORATION OF NEW YORK.

ELECTRIC SWITCH.

Application filed June 27, 1925. Serial No. 39,887.

This invention relates to electric switches in general and more particularly to improvements in high current carrying switches such as disclosed in my Patent No. 1,045,773, for a 5 "quick action electric switch," dated November 26th, 1912.

It has been found desirable to obtain a switch of appreciable capacity which is positively actuated into open or closed position 10 after the actuating means have been moved into actuating position by the initiating or operating means.

It is also an object of this invention to provide a switch in which, after the operating means has been moved a predetermined amount, said switch will be positively actuated to move into open or closed position.

It is further an object of this invention to provide a high power snap switch having 20 spring impelled actuating means, said means being adapted to be set in operating position by lever operated cam mechanisms.

With the above and other objects in view, as will be apparent, this invention consists 25 in the construction, combination and arrangement of parts, all as hereinafter more fully described, claimed and illustrated in the accompanying drawings.

On the drawings:

30 Figure 1 represents a longitudinal section of an improved switch embodying features of the present invention with the switch in open position.

Figure 2 is a plan view partly in section 35 when the switch is closed and with parts omitted.

Figure 3 is a detail sectional view taken on line III—III of Figure 2.

Figure 4 is a detail sectional view taken on 40 line IV—IV of Figure 2.

As shown on the drawings:

The structure selected for illustration comprises a base 1 on which is mounted a plate 2 of non-conducting material. Secured on 45 the plate 2 is a pair of flanged supporting members 3. The supporting members 3 have secured thereon an upper plate 4 of non-conducting material. Mounted on the plate 4 is a pair of contact binding posts 5 which 50 are adapted to be connected to their respective contact plates 6 through the fuses and mountings 7 therefor. As shown in Figure 3 the plates 6 are connected to their corresponding binding posts 7^a by means of 55 the conductors 8. Communicating with the

binding posts 7^a are contact members 9. Opposite to the contact members 9 are contact members 10. The contact members 10 are provided with binding posts 11. Extending between the supporting members 3 is a 60 sliding block or carriage 12 which has projecting therefrom at either end lugs 13 which engage in slots 14 in the members 3. The carriage 12 has clamped thereto at its lower side a bar 14^a by means of bolts 15. Secured 65 between the bar 14^a and the carriage 12 are a plurality of laminated switch members 16 which when the carriage 12 is in its lowermost position are adapted to connect the contact members 9 and 10. Extending through 70 the members 3 are a pair of rotatable rods 17 and 18. The rod 17 has rigidly secured thereon outside of the supporting members 3 a pair of cam members 19 and 20. The cam members 19 and 20 are similar in shape with 75 the exception that the cam member 19 has provided thereon an extension 21 to which is pivotally secured a rod 22. The rod 22 extends through and is slidable in an aperture 80 in a bracket member 23. The bracket member 23 is secured to the base 1. Rigidly secured on the rod 18 are a pair of arms 24 and 25. One end of each of the arms 24 and 25 is slotted to engage the projecting lugs 13 of the carriage 12. The other end of the arm 24 85 is pivotally secured to a rod 26 which is slidably mounted in a bracket 27 secured on the base 1. Surrounding the rods 22 and 26 are compression springs 28 and 29, respectively. The cam members 19 and 20 are provided 90 with projecting lugs 30 and 31 which are adapted in turn to engage the lugs 13. Secured on the plate 1 is a panel member 32 which has pivoted therein an operating cam 33 which has connected thereto an operating lever 34. Suitable stop members (not shown) 95 are provided on the panel member 32 for limiting the rotative movement of the lever 34. On the cam 33 there is provided a pair of angularly spaced radially extending members or lugs 35 and 36. Axially extending 100 on the projection 21 of the cam member 19 is a lug 37 which is adapted to be engaged in turn by the members 35 and 36 for alternately rotating the shaft 17.

In operation, when it is desired to close the switch from the open position shown in Figure 1 and in dotted lines in Figure 3, the lever 34 is moved in a clockwise direction. The member 35 of the cam 33 will engage 105

the projection 37 of the cam 19, causing the latter to rotate in a clockwise direction. As soon as the cam 19 has been rotated sufficiently to bring the pivotal point of the slideable rod 22 beyond dead center, the spring 28 will positively rotate the cams 19 and 20, causing the projections 31 thereon to engage with the projections 13 of the carriage 12 to move the latter downwardly to closed position, thereby closing the switch with a quick snap.

When it is desired to move the switch to open position, the handle 34 is moved backwardly, and a reversal of the above described 15 operation takes place. It will be noted that as soon as the cam members 19 and 20 have caused the carriage 12 to move downwardly beyond the central point of movement in slots 14 so that the pivotal connection between the rod 26 and the arm 24 has passed 20 its dead center, the spring 28 together with the spring 29 will assist in unison to positively actuate the switch and it will act to hold the switch in closed position until the 25 cams 19 and 20 have again moved the switch at least one-half way towards its open position. When the switch carriage has been moved beyond the central point of movement in slots 14 toward open position, the 30 spring 29 will become effective in assisting in the upward movement of the carriage just as it assisted in its downward movement. It will be obvious that this construction provides a means for positively actuating a 35 switch of appreciable current carrying capacity. It will be apparent to those skilled in the art that by providing a quick make and break mechanism which is set in operation by operating the lever 34 a predetermined amount, a very efficient switch is obtained which insures that the switch be positively in either open or closed position.

I am aware that many changes may be made, and numerous details of construction 45 may be varied through a wide range without departing from the principles of this invention, and I therefore do not purpose limiting the patent granted hereon, otherwise than necessitated by the prior art.

50 I claim as my invention:

1. An electric switch, operating means therefor, actuating means for positively actuating said switch to open or closed position, said actuating means being responsive 55 to said operating means when the latter is in a predetermined position, and resilient means associated with said actuating means for positively actuating said switch, said resilient means being responsive to said actuating means when the latter has been actuated a predetermined amount.

2. An electric switch comprising a pair of spaced contact members, a laminated switch member for coaction therewith, a movable 60 support for said laminated switch member,

cams for actuating said support and switch member, and spring controlled means adapted to cause operation of said cam members to move said switch member into and out of engagement with said contact members. 70

3. An electric switch comprising contact members, a slideable laminated switch device, cams for operating the same, means for selectively governing the operation of said cams, and spring controlled means responsive to a predetermined movement of said governing means to open and close said switch. 75

4. An electric switch comprising contact members, a slideable carriage, a laminated switch member carried by said carriage, cams for operating said carriage, spring controlled mechanisms adapted at predetermined times to actuate said cams, and a control device for rendering said spring controlled mechanisms active. 80

5. An electric switch comprising a base, contact members thereon, a movable carriage, a laminated switch member carried 90 by said carriage for coaction with said contact plates, a rotatable shaft, cams supported on the ends thereof, projections on the ends of said carriage in the path of said cams, a spring controlled mechanism for operating 95 said cams at predetermined times to engage said projections to move said carriage into and out of engagement with said contact members, and lever operated means for initially operating said spring controlled mechanism. 100

6. A switch comprising a base, slotted supports thereon, laminated switch means slideable with reference to said supports, a rotatable shaft, cams thereon adapted to coact 105 with said laminated switch means, a rod pivotally connected with one of said cams, a spring engaged on said rod, a projection on said rod, and lever operated means adapted to coact with said projection to move said 110 rod past a dead center position to permit the spring to cause said cams to actuate said laminated switch means.

7. A switch comprising a movably mounted laminated switch means, cams for actuating the same, spring controlled means for operating said cams, lever operated means for selectively governing the operation of said spring controlled means, and a spring controlled mechanism coacting with said 120 laminated switch means to hold the same in open and closed positions. 115

8. An electric switch of the class described comprising a slideably mounted switch member, a cam for actuating the same, a rod 125 pivotally connected to said cam, a spring on said rod, a projection on said cam, means adapted to coact with said projection to cause the spring to actuate said cam at a predetermined time to operate said switch 130.

member, and a spring controlled mechanism associated with said switch member and adapted to be initiated by the operation of said cam to hold the switch member in closed 5 and open position.

9. A switch comprising a movable switch member, a cam coacting therewith to move the same into open and closed position, a slotted support, a rod pivotally connected 10 to said cam and slidably engaged in said support, a spring on said rod between said sup-

port and said cam means for moving said rod and support past a dead center position to permit the spring to cause the cam to positively actuate said switch member, and 15 spring controlled means associated with said switch member for holding the same in open and closed positions responsive to the operation of said cam.

In testimony whereof I have hereunto subscribed by name.

JOHN A. COLE.
